(57) **CLAIM**

The ornamental design for a drink cooler as shown and described.

DESCRIPTION

FIG. 1 is a top right perspective view of the drink cooler of the present invention with an environmental view of a first handle embodiment;

FIG. 2 is a right side view thereof;

FIG. 3 is a left side thereof;

FIG. 4 is a front view thereof;

FIG. 5 is a back view thereof;

FIG. 6 is a top view thereof;

FIG. 7 is a bottom view thereof;

FIG. 8 is a bottom left perspective view thereof;

FIG. 9 is a top left perspective view of the drink cooler of the present invention with an environmental view of a second handle embodiment;

FIG. 10 is a right side view thereof;

FIG. 11 is a left side thereof;

FIG. 12 is a front view thereof;

FIG. 13 is a back view thereof;

FIG. 14 is a top view thereof;

FIG. 15 is a bottom view thereof; and,

FIG. 16 is a bottom right perspective view thereof.

The portions of the drink cooler illustrated in broken lines form no part of the claimed design.

1 Claim, 16 Drawing Sheets
